UNITED STATES PATENT OFFICE.

DELBERT WELLS, OF PAOLI, INDIANA.

AUTOMATIC SPARK-TIMING MECHANISM.

1,309,924.

Specification of Letters Patent. Patented July 15, 1919.

Application filed January 3, 1918. Serial No. 210,170.

To all whom it may concern:

Be it known that I, DELBERT WELLS, a citizen of the United States, residing at Paoli, in the county of Orange and State of Indiana, have invented certain new and useful Improvements in Automatic Spark-Timing Mechanism, of which the following is a specification.

This invention is an automatic spark timing mechanism for internal combustion engines and is more particularly adapted for use upon self propelled vehicles, wherein the time of ignition is automatically advanced and retarded in accordance with the varying engine speeds and the explosive mixture supplied at the different speeds, where the mixture changes from a rich mixture as used at idling and at low speeds to a relatively lean mixture supplied at the higher speeds and effect an economy of fuel with a maximum amount of power generated, independently of the control of the operator.

One object of the invention is to provide a device that will automatically vary the time of ignition through governing instrumentalities.

Another object of the invention is to provide a device that employs a governing instrumentality that includes a slidable member positively actuating or rotating the timer and distributor to vary the time of ignition in conformity with engine speeds and the expenditure supplied.

A further object of the invention is to provide a device that will automatically change the time of ignition or firing the explosive charge in the cylinder independently of manual control to lessen the chances of improper time of firing, due to the human equation.

Broadly stated, the invention comprises a member secured to a driving or operating shaft, pivotally mounted centrifugal elements carried by the member, said elements being provided at one end with fingers that are adapted to engage with a grooved member slidable on said shaft, resilient means operably connected with the centrifugal elements to vary the degree of movement upon rotation of the shaft, and adjustable means for connecting the timer and distributor with the slidable member.

One practical form of construction and assembly will be described and illustrated in the accompanying drawings, in which:—

Figure 1 is a side elevation of the assembled device,

Fig. 2 is a top plan view of the assembly,

Fig. 3 is an end elevation looking at the left hand end of Fig. 1, and

Fig. 4 is a sectional view on the line 4—4 of Fig. 1.

In the preferred embodiment as illustrated by the assembly shown in the accompanying drawings, a rotatably mounted shaft 5 is carried in the pedestal bearings 6 and 7. These bearings are preferably spaced apart and in alinement so that the shaft 5 may rotate freely therein. The bases of these bearings 6 and 7 may be provided with the usual holes to permit of the employment of the foundation bolts indicated at 8.

As shown in Fig. 2 these bearings 6 and 7 are secured by means of the foundation bolts 8 to a channel member 9 forming one of the frame members of a self propelled vehicle. The bearings may be supplied with the usual or customary lubricating cups 10. The shaft 5 may project beyond the bearing 6 and be provided with a driving pulley 11 as shown in Figs. 1 and 2. The pulley may be driven by means of a belt 12.

The inner ends of the bearings 6 and 7 are provided with suitable screw holes to permit of the attachment of the brackets 13 and 14. These brackets are provided at their lower ends with suitable curved feet indicated at 15 and 16. The curvature of the feet is such that they may lie in close contact with the bearings 6 and 7. These feet are also supplied with holes through which are adapted to pass suitable securing means such as the screws 17. As shown in Fig. 3 these pedestal bearings are spaced from and slightly above the channel member 9 by means of the curved arms 18 and 19, 18 being more particularly shown in this figure.

The upper ends of the brackets 13 and 14 are recessed to provide the tongues 20 and 21. These tongues are provided transversely with suitable holes through which pass the fastening means 22 and 23, which may be pins. To coöperate with the brackets 13 and

14 there is provided a supporting bar 24. This bar is provided with a slot at each end to coöperate with the tongues 20 and 21. To provide for the passing of the bolts 22 and 23 5 the forked ends of the bar are provided transversely with suitable holes.

At a suitable point preferably near the bearings 7 the bar 24 is provided with a curved section 25. A lever 26 is pivotally 10 mounted at 27 upon the bar 24. As shown in Fig. 1 the lever 26 is positioned transversely and one end is formed to provide an attachment for the rod 28. The rod 28 is preferably secured so that there may be relative movement between the lever 26 and the 15 rod 28. The lower end of the lever 26 is preferably formed in such a manner that a suitable finger 29 is provided. This finger may be of any usual type of construction 20 but is shown as having a rounded end indicated at 30.

The other end of the rod 28 connects with a bell-crank lever generally indicated at 31. This bell-crank lever is pivotally mounted 25 on the bar 24, the pivotal mounting being shown at 32. The bell-crank lever 31 has provided in each arm thereof a series of holes indicated at 33 and 34. The other end of the rod 28 is adapted to be engaged 30 with the holes 33 as shown more particularly in Fig. 2. The holes 34 are adapted to receive one end of a rod 35, which may lead to a timer and distributor (not shown). The holes 33 and 34 are thus adapted to provide 35 an adjustable connection for the rods 28 and 35, and may be employed to vary the degree of movement imparted at the end of the rod 35.

The shaft 5 is provided at a suitable point 40 with a disk like member 36 that may be secured in position upon the shaft in the usual or customary way, one of which is indicated by means of the key 37. The disk member 36 is provided at oppositely disposed points 45 with the brackets indicated at 38 and 39. These brackets are adapted to provide a pivotal mounting 40 and 41 for the arms 42 and 43. In order to provide for this mounting the disk member 37 may be provided 50 with suitable slots to accommodate the arms 42 and 43.

The arms 42 and 43 are provided at their free ends with the spherical enlargements indicated at 44 and 45. These enlargements 55 constitute the usual balls commonly employed in centrifugally operated devices. Each of the balls is provided with ears or lugs 46, 47, 48, and 49. The lugs 46 and 47 are formed upon the ball 44, and the lugs 48 60 and 49 are formed upon the ball 45.

As shown more particularly in Fig. 4 the lugs 46 and 47 are provided with pins indicated at 50 and 51. These pins may serve as guides for the coil springs indicated at 52 65 and 53. If desired, the pins 50 and 51 may

be screwed or otherwise secured in the lugs 46 and 47. The springs 52 and 53 may have their ends secured in any suitable way to the lugs 46 and 47. The opposite ends of these springs may be secured to the nuts 54 and 70 55. These nuts serve as adjusting means and operate upon the threaded stems 56 and 57.

One end of each of the stems 56 and 57 passes through the nuts 54 and 55 and project within the springs 52 and 53. They will thus serve as guides for the springs. The lower or opposite ends of the threaded stems 56 and 57 are adapted to engage with the lugs 48 and 49. The stems 56 and 57 80 may be turned in and out through the lugs 48 and 49 so as to place the springs 52 and 53 under tension. They serve to vary the degree of movement upon rotation of the balls 44 and 45. The greater the extension 85 of the springs 52 and 53 the greater the resiliency encountered by the balls 44 and 45 moving outward by centrifugal action.

Mounted upon the shaft 5 is a member 58, and this member is adapted to slide on 90 the shaft. Near each end of the member it is provided with the circumferential grooves 59 and 60. As shown each end of the member 58 is provided with a suitable flange which forms one wall at each of the grooves. 95 The member 58 is provided with a hole therethrough that is of sufficient size to permit the member to readily slide to be moved axially on the shaft 5.

The groove 59 is adapted to have engaged 100 with it the finger 29 having the rounded end 30. The groove 60 is adapted to coöperate with the curved fingers 61 and 62 that are carried at one end of each of the arms 42 and 43. These curved fingers 61 and 62 preferably 105 extend from near the pivotal mounting 40 and 41. The ends of the fingers 61 and 62 ride in the groove 60 as shown in Fig. 1.

When the shaft 5 is rotated the disk 36 110 will also rotate and carry with it the arms 42 and 43. As the speeded rotation increases the balls 44 and 45 tend to move outward carrying with them the arms 42 and 43. As these arms are pivotally mounted at 115 41 and 42 the outward movement of the balls will cause the fingers 61 and 62 to engage with the flange formed upon the end of the slideable member 58. The member 58 being freely movable on the shaft 5 will be pulled 120 toward or to the left and nearer the disk 36.

The movement of the member 58 will at the same time cause the lever 26 to move through the engagement of the finger 29 with the groove 59. This movement of the 125 lever 26 causes a corresponding movement to be imparted to the rod 28. As the rod 28 is connected to one end or a limb of the bell crank lever 31 it will produce a movement in the rod 35. This rod 35 being connected to 130

the other limb of the bell crank-lever will thus be seen that it must move in accordance with any movement of the bell-crank lever.

If at any time it is desired to change the amount of throw or movement of the rod 35 its end is positioned in a different one of the holes 34, and the rod 28 is positioned in another one of the holes 33. This will change the corresponding and relative movement of the rod 35 when acted upon by the centrifugal elements operating upon the slidable member 58. This type of governor is very sensitive to change of speed and therefore the movement will be in exact accordance with the movements of the several members. As the rod 35 is connected with the timer and distributor this position will be varied in a manner similar to the movement imparted by the slidable member. The time of ignition will then be automatically varied to correspond with the engine speeds.

What is claimed is:

1. An automatic spark timing mechanism comprising longitudinally spaced bearings, a shaft rotatably mounted in the bearings, a vertical standard mounted on each bearing, a bar secured to the tops of the standards, a slidable sleeve mounted on the shaft, means carried by the shaft for operating the sleeve, a lever pivotally connected to the bar and engaging the sleeve, a lever pivotally connected to the top of the bar, a rod connecting the two levers, and a rod leading from the second mentioned lever to the timing mechanism.

2. An automatic spark timing mechanism comprising longitudinally spaced bearings, a shaft rotatably mounted in the bearings, a

vertical standard mounted on each bearing, a bar secured to the tops of the standards, a 40 slidable sleeve mounted on the shaft, a centrifugal governor connected to the shaft and engaging the sleeve, means for adjusting the tension of the centrifugal governor, a lever pivotally connected to the bar and engaging 45 the sleeve, a lever pivotally connected to the top of the bar, a rod connecting the two levers, and a rod leading from the second mentioned lever to the timing mechanism.

3. An automatic spark timing mechanism 50 comprising longitudinally spaced bearings, a shaft rotatably mounted in the bearings, a vertical standard mounted on each bearing, a bar secured to the tops of the standards, a 55 slidable sleeve mounted on the shaft and provided adjacent each end with an exterior groove, a disk keyed to the shaft adjacent the slidable sleeve, a centrifugal governor carried by the disk and adapted to engage the groove in one end of the sleeve, means 60 for adjusting the tension of the centrifugal governor, a lever pivotally connected to the bar and engaging in the groove in the end of the sleeve opposite to the one engaged by the centrifugal governor, a lever pivotally 65 connected to the top of the bar, a rod connecting the two levers, and a rod leading from the second mentioned lever to the timing mechanism.

In testimony whereof I affix my signature 70 in presence of two witnesses.
